J. A. BARRAKET

COLLAPSIBLE CHAIR

Filed Nov. 3, 1926

INVENTOR.
Jacob A. Barraket.
BY
Maurice Oppenheimer
ATTORNEY.

UNITED STATES PATENT OFFICE.

JACOB A. BARRAKET, OF BROOKLYN, NEW YORK.

COLLAPSIBLE CHAIR.

Application filed November 3, 1926. Serial No. 145,926.

This invention relates to collapsible chairs, such as used in theatres, automobiles and for other like purposes.

One object of the invention is to provide a chair of the character described having a seat and back interconnected for cooperative movement whereby said seat and back may be adjusted to suit the comfort of the occupant of the chair by simply shifting the seat with respect to its stanchion supports.

Another object of the invention is to provide a collapsible chair of the character described, the seat whereof may be foldable toward the back and at the same time capable when in open position of being shifted back and forth so as to provide greater aisle space where the chairs are combined in rows for theatres or the like purposes.

A further object of this invention is to provide an improved device of the character described comprising unit groups of one or more chairs, each having the movable parts thereof independent of each other, said parts being arranged and positioned so that they cannot cause injury to the occupants or the occupants' apparel while seated or moving in and about in said chairs.

A still further object of this invention is to provide an improved device of the character described comprising few and simple parts, which may be readily assembled to form a chair or group of chairs, and shall be relatively cheap to manufacture, and practical and efficient in operation to a high degree.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a side elevational view of one chair unit of a group of chairs embodying the invention, such as used for theatres, lecture halls, auditoriums, and the like purposes, the

seat and back being shown in retracted position.

Fig. 2 is a side elevational view of the improved chair showing the seat and back in maximum extended position, one of the stanchions being removed to expose the construction of the movable parts. 55

Fig. 3 is a view similar to Fig. 2 showing the seat and back in folded or collapsed position, one stanchion being removed to expose the movable parts. 60

Fig. 4 is a front elevational view of the improved chair, showing the seat in folded position. 65

Referring in detail to the drawing, 10 denotes a chair embodying the invention adapted particularly for theatres, and like purposes. Said chair is seen to comprise a pair 70 of side supports or stanchions 11 made of angle iron, each being bent into a suitable shape to form a substantial rigid structure, as shown in Figs. 1, 2 and 4. Between said stanchions there is mounted a movable seat 75 12 having a back 13. For supporting the seat between the stanchions, any suitable pivoted means may be provided, such as the fittings 14.

Each fitting 14 may have a socket 14^a which 80 is rigidly secured to a stanchion by riveted gusset plates 15, as shown in Fig. 1. A separate gusset plate and socket fitting are provided to extend from opposite sides of each stanchion (see Fig. 1) so that each stanchion 85 may serve as a support between two adjacent seats in the well understood manner and as indicated in dotted lines in Fig. 4.

Each pivoted fitting 14 includes a stub-shaft 14^b extending from opposite sides of 90 the seat 12 provided with an enlarged head 14^c, the latter being engaged in a socket 14^a, as is clearly shown in Fig. 1. Said socket has a slotted opening 14^d for entering the shaft head 14^b and may be provided with a removable closure plate 14^e firmly secured over said slotted opening for retaining the shaft head 14^c against accidental displacement. Said shaft head 14^c may be formed with a projecting portion having shoulders 14^f for engaging against suitable abutment stops formed in the socket 14^a for limiting the swinging movement of the seat 12. 95

The seat 12 may include an over-up-

holstered structure 12^a of any suitable well understood construction and is also supported for slideable movement with respect to the stanchions. For this purpose, a slideable 5 mounting is provided in the form of an angle bracket 16 from which the stub shafts 14^b project, as shown in Fig. 4. Said angle brackets form slideway supports on which the opposite edge portions of the seat 12 ride. The 10 underside of the seat is preferably provided with an edge reinforcing frame 12^b which has sections 12^c thereof contacting the angle brackets 16 to form a smooth sliding connection. To retain the seat 12 in sliding cooperative 15 position on said angle brackets 16, suitable means is provided comprising an elongated slot 16^a in each angle bracket 16 through which extend the stud bolts 17 for holding a retaining plate 18 whereby said 20 seat 12 is permitted to slide with respect to the angle brackets 16 and stanchions 11 for the purpose hereinafter described.

The back 13 is provided to the stanchions 11 in any suitable manner, as by means of a 25 fitting 19 which may be similar in construction to the fitting 14 which supports the seat 12. Said fitting 19 is seen to comprise a socket 19^a which is rigidly secured to an upper part of the stanchion, as shown in Figs. 30 1 and 4 and is adapted to receive an enlarged head portion 19^c of a stub shaft 19^b, a pair of 35 said shafts being provided to extend from opposite sides of the back 13. Said socket 19^a has a slotted opening 9^d for entering the shaft 40 head 19^b and may be provided with a removable closure plate 19^e firmly secured over said slotted opening for retaining the shaft head 19^c against displacement. Said shaft head 19^c may likewise be formed with a projecting 45 portion having shoulders 19^f for engaging against suitable abutment stops formed in 50 said socket fitting 19. Each of said shafts 19^a preferably projects from a mounting member 20 which supports the back 13 in position, as shown in Fig. 4. Extending from 55 the lower end portions of each of said members is an arm 20^a which extends below the seat and has a longitudinally extending slot 20^b therein in which rides a roller 21. Each 60 of said rollers is mounted for rotation on the end of a cross-shaft 22, the shaft being rigidly secured by means of straps 25 on the underside of the seat 12, as is clearly shown in Fig. 4. The arm 20^a is shaped so as to permit cooperative 65 movement between the seat 12 and back 13 in slideably extending or retracting the seat as seen in Figs. 1 and 3 and also to permit collapsibly folding the seat 12 toward the back 13, as is shown in Figs. 3 and 4.

60 For limiting the sliding movement of the seat 12 in the angle brackets, a suitable adjustable stop 23 may be secured on the underside of the seat against which the outer end of 65 said brackets 16 abut on retracting the seat

from its normal extended position, as is clearly shown in Fig. 1.

In order to prevent the upholstered structure of the seat 14 from catching or engaging with the angle brackets 16 and being injured thereby, guard plates 24 secured against the 70 sides of the upholstered structure 12^a adjacent said brackets 16 may be provided, as is clearly shown in Figs. 1 and 3.

The operation of the chair 10 will now be apparent. With the chair parts assembled 75 as shown in the drawing and the chair foldably collapsed, as shown in Figs. 3 and 4, the shoulders 14^f on the projection of the shaft head 14^c retain the seat 12 of the chair in vertical or closed position and the back 13 through its engagement with the seat by means of the slotted arm and roller connection is swung inwardly with respect to the stanchion 11. On swinging the chair into 80 open position, the roller 21 will ride in the slot 20^b of the arm 20^a and the parts will be disposed, as shown in Fig. 1. The occupant on taking the seat may easily adjust the chair by applying a slight pressure or force against the floor with his feet or his hands on the arms 85 26 of the chair for shifting same into a fully extended position, as shown in Fig. 2. In shifting the seat to its extended position, the back is simultaneously swung with its upper 90 end away from the stanchions. The occupant may thus adjust the seat and back of the chair 95 to suit his comfort.

Where a number of such chairs are united 100 into groups constructed in unit groups arranged in rows, the inventor provides means whereby occupied seats may be easily passed for ingress or exit from adjacent seats. The occupant of the seat simply retracts the seat by sliding the seat as explained above. It should be noted that the seat and back of the 105 chair when in collapsed position, as shown in Figs. 3 and 4 not only increases the available space in front of the seat but also behind the back, as is clearly seen from the drawing.

It will thus be seen that there is provided 110 a device in which the several objects of this invention are achieved, and which is well adapted to meet the conditions of practical use.

As various possible embodiments might be 115 made of the above invention, and as various changes might be made in the embodiment above set forth, it is to be understood that all matter herein set forth or shown in the accompanying drawing is to be interpreted as illustrative and not in a limiting sense.

Having thus described my invention, I claim as new and desire to secure by Letters Patent:—

1. In a collapsible chair of the character described, a seat having a back, operatively connected thereto, and a pivot for said seat having a fixed center, said seat being mounted

for sliding and rotative movement relatively to said pivot.

2. In a chair of the character described, a seat having a back, means for supporting the seat in an open extended and a closed position, including a fixed pivot for the seat and a slidable connection between the pivot and the seat, for allowing movement of said seat relatively to said pivot and thereby varying

10 the available passageway in front of the seat.

3. In a chair of the character described, a seat having a back, means for supporting the seat in an open extended and closed position, guide means for extending and retracting said seat in its open position for varying the available passageway in front of the seat, and means on the seat adapted to engage the guide means for adjusting the extending and retracting movement of the seat.

20 4. A chair of the character described comprising a seat having a back, stanchions provided with pivots having fixed tenders for movably supporting the seat and back, and means for retracting the seat and back from an extended open position whereby the available passageways in front of the seat and behind the back are increased.

5. A chair of the character described comprising stanchions, a seat collapsibly supported by said stanchions, and means including a pivoted member slidably connected to the seat for slidably moving the seat with respect to the stanchions to permit retracting the seat from an extended position whereby the available passageway in front of the seat is increased.

6. A chair of the character described comprising stanchions, a seat collapsibly supported by said stanchions, means for slidably moving the seat with respect to the stanchions to permit retracting the seat from an extended position whereby the available passageway in front of the seat is increased, and a back movably supported by said stanchions, a slotted member fixedly secured to said back and interconnected with said seat for simultaneous movement therewith into a retracted position to increase the available passageway behind said back.

50 7. A group of chairs connected together to form a unit, each chair having a collapsible seat, a movable back interconnecting with said seat, and means including a pivoted member rotatable about a fixed center for slidably retracting the seat in uncollapsed position, said seat when collapsed or retracted being adapted to increase the available passageways in front of the seat and behind the back of the chair.

60 8. A group of chairs connected together to form a unit, each chair having a collapsible seat, a movable back interconnecting with said seat, means for slidably retracting the seat in uncollapsed position, said seat when collapsed and retracted being adapted to in-

crease the available passageways in front of the seat and behind the back of the chair, and means on said seat adapted to engage the retracting means for limiting the retractive movement of the seat.

70

9. A chair of the character described comprising a pair of stanchions, a seat slidably and pivotally mounted between said stanchions, said seat being adapted to collapsibly fold against the back and slidably retracted from an open extended position to increase the available passage in front of the seat, a back for the seat swingably supported between said stanchions, and a slotted arm extending from said back interconnecting with said seat for simultaneously swinging the back on collapsing or retracting the seat to increase the available passageway behind the back of the chair.

75

10. In a chair of the character described, a seat including an upholstered structure, a member swingable about a fixed pivot for supporting the seat for sliding retractive movement whereby the available passageway in front of the seat is increased, guard plates secured against said upholstered structure adjacent said means to prevent injury to said structure.

80

11. In a chair of the character described, a seat, a back, means for pivotally supporting the seat and the back intermediate of the respective ends thereof, a slotted member mounted for rotation only on the supporting means for slidably connecting the seat and said member, a second slotted member secured to the back and mounted for rotation only on said supporting means, and means on the seat passing through the slot of said second slotted member for cooperating with the second member to partly rotate said back on the movement of said seat.

85

12. A mounting for a slidable seat comprising a fixed socket member having a slotted opening therein, a shaft having an enlarged head entering the socket member, and means on said head cooperating with the sides of the slot for limiting the rotative movement of the shaft, a slotted member associated with said shaft, and means for slidably connecting the slotted member to the seat.

90

13. In a chair of the character described, a seat, a back pivoted intermediate its ends, a slotted member operatively connecting the seat and the back, and a member having a fixed center rotatably and slidably supporting the seat.

95

14. In a chair of the character described, a seat, and means for rotatably and slidably supporting the seat comprising an angle member, a fixed pivot for said member on one of the legs thereof, and means operatively connected to the other legs of said member for slidably connecting the member and the seat.

100

15. In a chair of the character described, a seat, and means for rotatably and slidably

120

125

130

supporting the seat comprising an angle member, a fixed pivot for said member on one of the legs thereof, and means operatively connected to the other leg of said member for 5 slidably connecting the member and the seat, and means on said seat adapted to engage said member in the limiting positions of the seat.

16. In a chair of the character described,

a rotatable and slidable seat, a back, and a slotted member fixedly associated with the back and operatively connected to the seat whereby movement of the seat causes movement of the back. 10

In testimony whereof I affix my signature.

JACOB A. BARRAKET.
